UNITED STATES PATENT OFFICE.

SHERMAN I. KEHLER, OF WASHINGTON, DISTRICT OF COLUMBIA.

DIRIGIBLE AIRSHIP.

1,320,867.

Specification of Letters Patent.

Patented Nov. 4, 1919.

Application filed July 20, 1918. Serial No. 245,881.

To all whom it may concern:

Be it known that I, SHERMAN I. KEHLER, a citizen of the United States, and a resident of Washington, in the District of Columbia, have invented certain new and useful Improvements in Dirigible Airships, of which the following is a specification.

This invention relates to dirigible airships and the principal object of the invention is to provide a dirigible airship, the aerostat of which embodies a rigid skeleton, constructed in such manner as to develop the maximum strength of the greater part of the material employed in the skeleton structure; which object is attained by the employment of a pair of lateral side fins or ribs, a longitudinal vertically projecting fin and a keel for main strength or bracing members, all of which are placed at a maximum distance from the longitudinal axis of the aerostat.

Another object of the invention is to cover the rigid metallic skeleton with an envelop of strong but light fabric on which the resistance of the air is exerted during flight of the dirigible and to place within the rigid metallic skeleton of the aerostat a number of balloons inflated with hydrogen, the sum of whose lifting power constitutes the total ascensional effort of the dirigible.

A further object of the invention is to provide, in the construction of the metallic skeleton, a pair of diametrically opposed longitudinally extending lateral ribs which form the dual function of bracing the structure longitudinally and imparting a dynamic lift during the progress of the dirigible also to provide a longitudinally extending top fin or rib, the sides of which converge and which assists in maintaining the direction of flight of the dirigible particularly in strong head wind and which further, has a tendency to divide and direct the air current downwardly about the outer surface of the envelop during the lift of the dirigible.

Another object of this invention is to provide a dirigible airship as specified in which the rigid skeleton provides means which dispenses with the necessity of the employment of air ballonnets in the pisciform dirigible or any type which ordinarily requires a ballonet to prevent the envelop from becoming flaccid due to the loss of hydrogen, and consequently losing its original shape and compromising its general equilibrium.

Other objects of the invention will appear in the following detailed description, taken in connection with the accompanying drawings, forming a part of this specification, and in which drawings:

Figure 1 is a perspective view of the improved dirigible airship.

Fig. 2 is a longitudinal horizontal section of the air ship.

Fig. 3 is a vertical section through the airship.

Fig. 4 is an enlarged fragmentary view of the airship.

Fig. 5 is a perspective view of one of the longitudinal bracing ribs of the rigid metallic skeleton.

Fig. 6 is a diagrammatic view illustrating the construction of the keel of the dirigible.

Referring more particularly to the drawings, 1 indicates the aerostat of the dirigible as an entirety, which includes a rigid skeleton frame indicated at 2, and composed of a plurality of longitudinally extending ribs 3 constructed of aluminum or other light material and being substantially the shape of an equilateral triangle in cross section. The longitudinally extending ribs 3 are connected by relatively short ribs 4, extending from one longitudinal rib to the one next thereto, circumferentially of the aerostat 1. The rigid metallic skeleton 2 is braced by a plurality of longitudinally extending ribs or fins 5, 6 and 7, as well as by the keel structure 8. The fins or ribs 6 and 7 are positioned in diametrically opposed relation and are right angular triangular in cross section having the bases 9 of which preferably aline with the center of the aerostat 1 and which ribs or braces project beyond the outer surface of the aerostat for imparting a dynamic lift to the aerostat during travel of the same as well as bracing the rigid metallic skeleton. These ribs or fins 6 and 7 are composed of a plurality of longitudinally extending angular corner braces indicated at 10 which are connected by cross braces indicated at 11.

The top centrally disposed longitudinally extending rib or fin 5 is the shape of an equilateral triangle in cross section, having its base toward the center of the aerostat while its apex projects beyond the outer surface of the aerostat forming a longitudinally extending brace for the rigid metallic

skeleton 2 and also assisting in the maintaining of directional travel of the dirigible particularly during heavy head winds. The positioning of the apex of this rib or fin 5 outwardly, will also have a tendency to split and guide the air current downwardly along the outer surface of the upper portion of the aerostat during the lifting movement of the dirigible.

10 Fig. 5 shows a fragmentary perspective view of the rib 5 illustrating the manner of building up or constructing this rib. The rib or fin 5 is built up from angular corner brace structures 13 each of which is the 15 shape of an equilateral triangle in cross section and comprises longitudinally extending angled pieces 14 connected by straight braces 15 and diagonal braces 16. These corner braces or bracing members 13 are in turn connected by straight or parallel 20 braces 17 and diagonal braces 18 to form the skeleton frame of the rib 5. All of the braces and angled members of the various rib structures are preferably constructed of 25 aluminum for providing a strong rigid and yet light skeleton frame.

The interior of the skeleton frame 2 is divided into a plurality of compartments by suitable wires or rods 19 which have their 30 outer ends connected to the longitudinally extending ribs 3 and their inner ends connected to the annular flanges 20 of collars 21. The collars 21 are positioned at the longitudinal axis of the skeleton frame and 35 are keyed or otherwise suitably attached to a cable 22. The cable 22 extends throughout the entire length of the aerostat and has one end attached to a suitable cap 23 attached to the tail end of the aerostat 1 and 40 its other end connected to a bolt 24 which is adjustably carried by a cap 25 at the nose end of the aerostat. By adjusting the position of the bolt 24 with respect to the nose cap 25, the tension upon the skeleton frame 45 may be regulated as desired.

The aerostat 1 contains a number of balloons 26, one being positioned in each of the compartments formed by the radiating wires or rods 19 and these balloons are inflated 50 with hydrogen. The sum of the lifting power of the balloons 26 constitutes the total ascensional effort of the dirigible. The various balloons 26 are shaped to snugly fit within the skeleton frame 2, as clearly 55 shown in Fig. 2 of the drawings and they are provided with axial sleeves 27 of the usual construction in balloons of this nature through which sleeves the cable 22 extends. The ordinary type of valve may be employed 60 for inflating and deflating the balloons. When inflated, the balloons are held from engagement with the framework of the skeleton 2 by a protecting netting 28 of relatively fine cord or other suitable material which is positioned inwardly of the

inner surfaces of the various longitudinal and circumferential braces 3 and 4 respectively, as shown in Fig. 4 of the drawings. The radiating wires 19 prevent deformation of the various balloons 26.

70

The keel 8 extends longitudinally along the center of the lower portion of the rigid skeleton frame 2 diametrically opposite of the rib 5 and it is made up of angular members or braces 26 and suitable cross and diagonal braces 27 in the same manner in which the rib or fin 5 is constructed as shown in Fig. 5 of the drawings.

75

The keel 8 is illustrated in the drawings as positioned exteriorly of the body of the 80 aerostat, but it is to be understood that this keel may be positioned within the body if it is so desired, without departing from the spirit of this invention. The keel 8 preferably contains the cabin for passengers, 85 space for cargo, fuel tanks, equipment, supplies and various control levers and mechanism of the dirigible. The engines and propellers 28 of the dirigible may be carried by suitable supports 29 which project 90 outwardly from the keel 8, one from each side of the keel as shown in Fig. 3 of the drawings.

95

In Fig. 6 of the drawings, a modified form of the construction of the keel is shown. 95 In this form, the keel 8^a is composed of corner bracing members 26^a which are substantially W-shaped in cross section forming a more substantial structure than that illustrated in Fig. 3 of the drawings, however the specific construction of the keel 8, or 8^a and the various ribs or fins 5, 6 and 7 form no part of this invention, such construction being left to the desire of the manufacturer and as necessity may require.

100

The aerostat 1 has the usual vertical and lateral stabilizing or empennage fins 30 and 31 carried thereby and placed behind the center of gravity of the aerostat while the usual type of elevating plane indicated at 110 32 and rudder indicated at 33 are also provided.

105

The entire skeleton 2 of the aerostat, as well as the various longitudinally extending ribs or fins are covered with an envelop of 115 strong but light fabric on which the resistance of the air is exerted during progress of the dirigible and which envelop is held spaced from the various balloons 26, by the skeleton 2 and netting 28, providing an air 120 space between the balloons and envelop and also preventing the overheating of the hydrogen within the balloon during the travel of the dirigible.

120

It will be noted by particular reference to 125 Figs. 1 and 2 of the drawings, that the horizontal ribs 6 and 7, and the keel 8 enter the envelop 35, near the rear end of the aerostat, or at the forward end of the various lateral and vertical fins 30 and 31 from 130

which point they extend to the tail or rear end of the aerostat within the envelop to prevent interference of their various planes or surfaces with the operation of the fins and elevating planes and rudders.

It is to be understood that the cable 22 may be eliminated in the construction of the dirigible, if desired, without departing from the spirit of this invention.

10 From the foregoing description taken in connection with the accompanying drawings, it will be apparent that a dirigible, the aerostat of which is pisciform in shape, which has a rigid metal skeleton, for maintaining the envelop against its becoming flaccid and eliminating the necessity of air ballonnets to maintain the original shape of the dirigible, has been provided and by the adjustment of the cable 22, the tension of 20 the rigid metallic skeleton and the various balloons 26 may be regulated as required.

Changes in details may be made without departing from the spirit or scope of the invention; but,

25 I claim:

1. In a dirigible airship, a pisciform aerostat comprising a rigid metallic skeleton including a plurality of longitudinal circumferentially spaced ribs, relatively short ribs 30 having their ends connected to adjacent longitudinal ribs and arranged to form spaced circumferential bracing for the skeleton, and a plurality of relatively large longitudinally extending strengthening ribs exteriorly of 35 the general contour of the aerostat and presenting flat inner sides to the aerostat.

2. In a dirigible airship, a rigid aerostat, a pair of diametrically opposed ribs extending longitudinally of the aerostat and presenting horizontal surfaces toward the under surface of the aerostat exteriorly of the 40 general contour of the aerostat and presenting flat inner sides to the aerostat.

3. In a dirigible airship, a rigid aerostat, 45 a trellis work rib extending longitudinally along the center of the uppermost portion of the aerostat and presenting inclined sides diverging toward the main contour of the aerostat.

50 4. In a dirigible airship, a rigid aerostat, a pair of diametrically opposed ribs extending longitudinally of the aerostat and presenting horizontal surfaces toward the under surface of the aerostat exteriorly of the 55 general contour thereof, a rib extending longitudinally along the center of the uppermost portion of the aerostat and presenting inclined sides diverging toward the main contour of the aerostat.

60 5. In a dirigible airship, a pisciform aerostat comprising a rigid metallic skeleton, a balloon within said skeleton, a pair of diametrically opposed ribs extending longitudinally of the aerostat and presenting horizontal surfaces toward the under surface of

the aerostat exteriorly of the general contour thereof and presenting flat inner sides to said balloon.

6. In a dirigible airship, a pisciform aerostat comprising a rigid metallic skeleton, a 70 plurality of balloons within said skeleton, a pair of diametrically opposed ribs extending longitudinally of the aerostat and presenting horizontal surfaces toward the under surface of the aerostat exteriorly of the general contour thereof and presenting flat inner sides to said balloon, and an envelop 75 inclosing said skeleton.

7. In a dirigible airship, a pisciform aerostat comprising a rigid metallic skeleton, a 80 balloon within said skeleton, a fabric envelop inclosing said skeleton, a netting holding said balloon from engagement with the skeleton, a pair of diametrically opposed ribs extending longitudinally of the aerostat 85 and presenting horizontal surfaces toward the under surface of the aerostat exteriorly of the general contour thereof.

8. In a dirigible airship, a pisciform aerostat comprising a rigid metallic skeleton, a 90 balloon within said skeleton, a netting holding said balloon from engagement with the skeleton, a rib extending longitudinally along the center of the uppermost portion of the aerostat, and presenting inclined sides 95 diverging toward the main contour of the aerostat.

9. In a dirigible airship, a pisciform aerostat comprising a rigid metallic skeleton including a plurality of longitudinal circumferentially spaced ribs, relatively short ribs 100 having their ends connected to adjacent longitudinal ribs and arranged to form spaced circumferential bracings for the skeleton, a plurality of relatively large 105 longitudinally extending strengthening ribs exteriorly of the general contour of the aerostat, said strengthening ribs each comprising longitudinal substantial triangularly shaped corner bracing members and 110 metal trellis work connecting said corner bracing members.

10. In a dirigible airship, a pisciform aerostat comprising a rigid metallic skeleton, a plurality of relatively large longitudinally extending strengthening ribs exteriorly of the general contour of the aerostat and presenting flat inner sides to the aerostat, said strengthening ribs each comprising longitudinal substantially triangularly shaped corner bracing members and 120 metal trellis work connecting said corner bracing members.

11. In a dirigible airship, an aerostat comprising a rigid metallic skeleton, a cable 125 extending longitudinally through the center of the aerostat, a plurality of disk mounted upon said cable, a plurality of radiating wires connected to said disks and to said metallic skeleton, a plurality of bal- 130

1. loons within said skeleton, said radiating wires preventing endwise deformation of the balloons, a netting within said skeleton for preventing engagement of the balloons with the skeleton, a pair of diametrically opposed ribs extending longitudinally of the aerostat and presenting horizontal surfaces toward the under surface of the aerostat exteriorly of the general contour thereof.
2. In a dirigible airship, an aerostat comprising a rigid metallic skeleton, a cable extending longitudinally through the center of the aerostat, a plurality of disks mounted upon said cable, a plurality of radiating wires connected to said disks and to said metallic skeleton, a plurality of balloons within said skeleton, said radiating wires preventing endwise deformation of the balloons, a netting within said skeleton for preventing engagement of the balloons with the skeleton, a pair of diametrically opposed ribs extending longitudinally of the aerostat and presenting horizontal surfaces toward the under surface of the aerostat exteriorly of the general contour thereof, a rib extending longitudinally along the center of the uppermost portion of the aerostat and presenting inclined sides diverging toward the main contour of the aerostat.
3. In a dirigible airship, an aerostat comprising a rigid metallic skeleton, a cable extending longitudinally through the center of the aerostat, a plurality of disks mounted upon said cable, a plurality of radiating wires connected to said disks and to said metallic skeleton, a plurality of balloons within said skeleton, said radiating wires preventing endwise deformation of the balloons, a netting within said skeleton, for preventing engagement of the balloons with the skeleton, a pair of diametrically opposed ribs extending longitudinally of the aerostat and presenting horizontal surfaces toward the undersurface of the aerostat exteriorly of the general contour thereof, a rib extending longitudinally along the center of the uppermost portion of the aerostat and presenting inclined sides diverging toward the main contour of the aerostat, and a fabric envelop inclosing said skeleton and said longitudinal ribs.
4. In a dirigible airship, a pisciform aerostat comprising a rigid metallic skeleton, a balloon within said skeleton, a fabric envelop inclosing said skeleton, a netting holding said balloon from engagement with the skeleton, a pair of diametrically opposed ribs extending longitudinally of the aerostat and presenting horizontal surfaces toward the under surface of the aerostat exteriorly of the general contour thereof, and a trellis work keel formed longitudinally along the center of the lowermost portion of the aerostat.
5. In a dirigible airship, a rigid aerostat comprising a rigid metallic skeleton, a plurality of relatively large longitudinally extending strengthening ribs exteriorly of the general contour of the aerostat and presenting flat inner sides to the aerostat, said strengthening ribs each comprising longitudinal corner bracing members and a metal trellis work connecting said corner bracing members, a pair of said strengthening ribs being diametrically opposed and presenting flat horizontal surfaces toward the undersurface of the aerostat.
6. In a dirigible airship, a rigid aerostat, a pair of diametrically opposed ribs extending longitudinally of the aerostat and presenting horizontal surfaces toward the under surface of the aerostat exteriorly of the general contour thereof, a rib extending longitudinally along the center of the uppermost portion of the aerostat and presenting inclined sides diverging toward the main contour of the aerostat, and a trellis work keel formed longitudinally along the center of the lowermost portion of the aerostat.
7. In a dirigible airship, a rigid aerostat, a pair of diametrically opposed ribs extending longitudinally of the aerostat and presenting horizontal surfaces toward the under surface of the aerostat exteriorly of the general contour thereof, a rib extending longitudinally along the center of the uppermost portion of the aerostat and presenting inclined sides diverging toward the main contour of the aerostat, a trellis work keel formed longitudinally along the center of the lowermost portion of the aerostat, a cable extending longitudinally through the center of the aerostat, and adjustable means connected to one end of the cable to regulate longitudinal tension on the aerostat.
8. In a dirigible airship, a rigid aerostat, a rib extending longitudinally along the center of the uppermost portion of the aerostat and presenting inclined sides diverging toward the main contour of the aerostat, said rib comprising longitudinal substantially triangularly shaped corner bracing members and trellis work connecting said corner bracing members.
9. In a dirigible airship, a rigid aerostat, a pair of diametrically opposed ribs extending longitudinally of the aerostat and presenting horizontal surfaces toward the under surface of the aerostat exteriorly of the general contour thereof, a cable extending longitudinally through the center of the aerostat, and adjustable means connected to one end of the cable to regulate longitudinal tension on the aerostat.
10. In a dirigible airship, a rigid aerostat, a rib extending longitudinally along the center of the uppermost portion of the aerostat and presenting inclined sides diverging toward the main contour of the aerostat.

- toward the main contour of the aerostat, a cable extending longitudinally through the center of the aerostat, and adjustable means connected to one end of the cable to regulate 5 longitudinal tension upon the aerostat.
21. In a dirigible airship, a rigid aerostat, a rib extending longitudinally along the center of the uppermost portion of the aerostat and presenting inclined sides diverging 10 toward the main contour of the aerostat and a flat inner surface to the aerostat.
22. In a dirigible airship, a pisciform aerostat, a plurality of balloons within said aerostat, means preventing deformation of 15 the balloons, caps upon the nose and tail end of the aerostat, means extending centrally through the aerostat for regulating longitudinal tension upon the aerostat, a rib extending longitudinally along the center of 20 the uppermost portion of the aerostat and presenting inclined sides diverging toward the main contour of the aerostat, said rib gradually decreasing in height toward said caps.
23. In a dirigible airship, a pisciform aerostat comprising a rigid metallic skeleton, a plurality of balloons within said skeleton, a cable extending longitudinally through the center of the balloon, adjustable means 30 connected to one end of the cable to regulate longitudinal tension upon the aerostat, said balloons provided with self closing openings in the center of their end portions adapted to receive said cable therethrough.
24. In a dirigible airship, a pisciform aerostat, comprising a rigid skeleton including a plurality of longitudinal circumferentially spaced ribs, relatively short ribs having 35 their ends connected to the adjacent longi-
- tudinal ribs and arranged to form spaced 40 circumferential bracing for the skeleton, an axial tensioning member within the aerostat, a plurality of disks mounted upon said tensioning member, and radiating wires connected to said disk and said skeleton frame 45 at the connection of said longitudinal relatively short ribs.
25. In a dirigible airship, a pisciform aerostat, comprising a rigid skeleton including a plurality of longitudinal circumferentially spaced ribs, relatively short ribs having 50 their ends connected to the adjacent longitudinal ribs and arranged to form spaced circumferential bracing for the skeleton, an axial tensioning member within the 55 aerostat, a plurality of disks mounted upon said tensioning member, and radiating wires connected to said disk and said skeleton frame at the connection of said longitudinal relatively short rib, a plurality of balloons 60 within said skeleton, one balloon being positioned within each adjacent set of said radiating wires, said wires preventing endwise deformation of said balloons.
26. In a dirigible airship, a pisciform 65 aerostat, comprising a rigid skeleton including a plurality of longitudinal circumferentially spaced ribs, relatively short ribs having their ends connected to adjacent longitudinal ribs and arranged to form spaced 70 circumferential bracing for the skeleton, a plurality of relatively large longitudinally extending strengthening ribs of trellis work and positioned exteriorly of the general contour of the aerostat, and an envelop inclosing 75 said skeleton and strengthening ribs.

SHERMAN I. KEHLER.
